ATTORNEY

UNITED STATES PATENT OFFICE

BENJAMIN COHEN, OF BROOKLYN, NEW YORK

FOUNDATION FOR ANIMAL HEAD AND BODY

Application filed April 30, 1932. Serial No. 608,409.

My invention relates to the interior construction of the head and body filler used in making up fur skins for neck wear and similar purposes.

It is the general practice in the fur mounting art to provide an animal head filler of resilient material preferably rubber which is cast or moulded in a single unit and of such shape as to accommodate the head skin to be fashioned. The filler because it is in a single piece includes not only the skull portion, but the tapering snout portion as well, and in order to improve the efficiency of the device the rubber used in the snout must be fairly rigid while the head or skull must retain a certain amount of resiliency to give it a more natural feel. It is not denied that the foregoing construction has its advantages, but these are quite negligible as compared with the disadvantage manifested in the weight of the article.

With the foregoing clearly in mind it is the purpose of my invention to construct a filler for an animal head fur piece which will embody all of the advantages of any of the well known devices of this character with the added advantage that it is extremely light in weight.

Another purpose of the present invention is to provide means embodied in the structure of the head filler to be in readiness during the fashioning of the fur skin to receive and carry the body filler into the skin as the latter is reversed and completed.

I accomplish these objects by means of the embodiment of my invention illustratively exemplified in the accompanying drawing, in which Figure 1 is a substantially longitudinal sectional view of a fur skin completely mounted and fashioned for use as a neck piece; Figure 2 is a perspective view of the head filler showing the body filler tape extended; Figure 3 is a substantially longitudinal sectional view of the head filler showing the body filler tape folded inside the first filler; Figure 4 is a perspective view of the under side of the skull and snout removed from the base.

Referring to the drawing, 10 denotes the fur skin constituting the animal head and 11

the trailing or body portion. The skin in accordance with the usual practice is tubular except for the portion adjoining the head, which portion is allowed to remain open so as to accommodate the head during the reversing operation, a step which is well known in this art and requires no detailed description here.

In accordance with my invention the filler for the head comprises a flat cardboard base 12 having a wide portion at one end and a tapering portion at the other end. The wide portion of the base 12 constitutes the foundation for the skull which comprises a dome shaped piece of sponge rubber 13 which is inherently light in weight and resilient in construction, and which is adapted to support, in life-like manner, the head skin 10 and to receive the shanks 14 of a pair of eyes 15 inserted into the proper places in the fur. The tapering portion of the base 12 comprises the foundation for the snout and on its under side, adjacent the free end, a metal loop 16 is mounted to receive and hold the upper member 17 of a spring operated jaw 18. The snout filler structure is built up of a strip of wood 19 which is mounted in upright position along one of its longitudinal edges on the upper face of the cardboard base 12, the strip 19 projecting from the end of the latter rearwardly into a recess in the front wall of the sponge rubber skull 13. It will be clear that in accordance with this invention the filler is very simple in construction and extremely light in weight without sacrificing any of the important features necessary in a filler of this character.

In order to add to the practicability of a head filler for fur skins, I countersink the wide portion of the board base 12 into the under surface of the sponge skull 13, allowing a marginal wall of the latter to extend about all three adjacent sides of the board, as illustrated particularly clearly in Figures 3 and 4. The skull 13 is provided with a recess or chamber 20, which projects beyond the roof of the recess accommodating the wide portion of the base 12 from the rear wall of the sponge rubber skull forwardly. When the rubber is mounted upon the base 12 a

cloth tape 21 is interposed between the base and the roof of the recess and before it is placed in use its free end is folded on itself a number of times to form a roll which remains in the recess or chamber 20 until ready to be used, as hereinafter explained.

It should be explained that the sponge rubber skull 13, snout supporting wood piece 19, and cardboard base 12 are all provided with a coating of adhesive substance which enables the fur skin to adhere to the filler. The tape 21 is likewise provided with a coating of adhesive to cause the cotton or wool filler 22 to adhere thereto, the latter filler being used to stuff the body portion 11 of the skin.

In operation the skin is handled in a wet condition and except for the head portion the tubular skin is disposed inside out. The snout portion of the cardboard 12 and wood rib 19 are inserted into the snout portion of the fur skin and the latter is pressed against the filler to cause it to adhere thereto so that when the skin becomes dry it will become an integral part of its filler. Following this operation the head portion of the skin is worked over the skull foundation 13 and adhered thereto. The eyes 15 are then inserted to complete the head.

So far the tape 21 in its chamber 20 has remained dry because there has been no contact between it and the wet skin. It is now time to use the tape and to do so, the rear wall of the skull is pulled away from the end of the cardboard base 12 and the rolled tape is drawn out of the chamber and its free end unrolled, and affixed to a strip of the soft filler 22. The head portion is then turned back upon the neck portion of the skin and inserted in the opening therein. In this operation the tape 21 and the attached filler 22 follows the skull 13 into and through the tubular body of the skin as it is turned right side out. When the skin has been completely reversed, the filler 22 is in its proper position inside the body, without further attention being given to this detail.

Through the opening in the neck portion of the skin and on the under side thereof, the upper member 17 of the jaw is inserted so as to engage in the scabbard or metal loop 16. The lower portion 18 of the jaw remains outside and is yieldably held against the snout by its spring, as illustrated in Figure 1.

Having now described my invention, what I claim and desire to secure by Letters Patent is:

1. A foundation for an animal head and body, comprising a fur skin head and body portion, a foundation over which said head is fashioned, and a spring jaw having upper and lower members, said foundation comprising a sponge like skull portion, a flat base member upon which the skull portion is mounted, having a snout portion projecting

forward of the skull, an upright rib piece mounted on the snout portion and projected at one end into the skull, a projecting piece extending rearwardly of the skull to carry the filler into the body of the skin, and means on the snout portion to receive and hold the upper member of the spring jaw.

2. A foundation for an animal head and body, comprising a fur skin head and body portion, a foundation over which said head and body is fashioned and a spring jaw having upper and lower members, said foundation comprising a sponge like skull portion, a flat base member upon which the skull is mounted, having a snout portion projecting forward of the skull, an upright rib portion mounted on and projected the length of the snout and disposed at one end in the skull portion, a tape fastened to the foundation and trailing the skull to carry a filler into the body of the skin, and means carried on the under side of the snout portion of the base to receive and hold the upper member of the jaw.

3. An animal foundation, as claimed in claim 2, in which the skull is provided with a recess in its under surface to receive the base, and a second recess or chamber in communication with the first recess beneath the base to receive and contain the free end of the tape in rolled condition, said tape being freed for use by distorting a wall of the skull forming one side of the second recess.

4. An animal foundation, as claimed in claim 2, in which the skull is provided with a recess in its under surface to receive the base, and a second recess or chamber in communication with the first recess beneath the base to receive and contain the free end of the tape in rolled condition, said tape being freed for use by distorting a wall of the skull forming one side of the second recess, said tape being provided with an adhesive coating to attach the body filler thereto.

5. An animal foundation, as claimed in claim 2, in which the skull is provided with a recess in its under surface to receive the base, and a second recess or chamber in communication with the first recess beneath the base to receive and contain the free end of the tape in rolled condition, said tape being freed for use by distorting a wall of the skull forming one side of the second recess, said skull, base and tape being provided with an adhesive coating to attach the head to the skull and snout and the body filler to the tape.

6. A foundation for an animal head and body comprising a fur skin head and body portion, a foundation over which said head is fashioned in wet condition, and a spring jaw having upper and lower members, said foundation comprising a flat cardboard base with a broad skull portion and tapering snout portion, a loop on the underside of the snout

to receive and hold the lower jaw member, a sponge rubber skull mounted on the skull portion of the base, a projection piece extending rearwardly of the skull to carry the ³ filler into the body of the skin, and a wood strip mounted on and disposed longitudinally of the snout to rigidly support the snout portion of the skin.

7. A foundation for a skin as claimed in
10 claim 6, in which the sponge rubber skull is provided with a recess on its under side bounded by three marginal walls, and a second recess disposed deeper in the skull than the first and having a common rear wall with
15 the first recess, the rear wall projecting over the rear edge of the base to seal the second recess, a tape attached at one end to the foundation between the skull and base and rolled up in said second recess when not in use, the
20 rear wall of the skull being distorted to allow withdrawal of the free end of the tape, and a body filler attachable to said tape to be drawn into the body portion of the skin.

8. A foundation for a skin as claimed in
25 claim 6, in which the sponge rubber skull is provided with a recess on its under side bounded by three marginal walls, and a second recess disposed deeper in the skull than the first and having a common rear wall with
30 the first recess, the rear wall projecting over the rear edge of the base to seal the second recess, a tape attached at one end to the foundation between the skull and base and rolled up in said second recess when not in use, the
35 rear wall of the skull being distorted to allow withdrawal of the free end of the tape, and a body filler attachable to said tape to be drawn into the body portion of the skin, and
40 artificial eyes having means inserted into the skin and skull on opposite sides of the up-standing snout rib.

In testimony whereof he has affixed his signature.

BENJAMIN COHEN.
